PHOTOGRAPHIC CABINET

Filed July 30, 1925

FIG. 1

Patented Mar. 16, 1926.

1,576,674

UNITED STATES PATENT OFFICE.

ROBERT E. OLSEN, OF OCEAN PARK, CALIFORNIA.

PHOTOGRAPHIC CABINET.

Application filed July 30, 1925. Serial No. 46,941.

To all whom it may concern:

Be it known that I, ROBERT E. OLSEN, a citizen of the United States, residing at Ocean Park, in the county of Los Angeles and State of California, have invented a certain new and useful Improvement in Photographic Cabinets, of which the following is a full, clear, and exact description, reference being had to the accompanying drawings.

This invention relates to photographic cabinets.

The general object of the invention is to provide an improved cabinet for use with automatic photographic machines.

One of the specific objects of the invention is to provide a photographic cabinet including means to exclude light from the subject being photographed.

Another object of the invention is to provide a photographic cabinet including means for excluding light from the face of the subject while at the same time providing artificial light so that shadows are eliminated.

Another object of the invention is to provide a photographic cabinet wherein means is provided for automatically shifting the illuminating light when the seat is raised or lowered.

Other objects of the invention will be apparent from the following description taken in connection with the accompanying drawings wherein:

Fig. 1 is a perspective view of a photographic cabinet embodying the features of my invention.

Fig. 2 is a sectional view of the cabinet taken on line 2—2, Fig. 3, and

Fig. 3 is a sectional view of the cabinet taken on line 3—3, Fig. 2.

Referring to the drawing by reference characters I have indicated my cabinet generally at 10. This cabinet includes a base 11 having a back 12 thereon upon which a cabinet 14 is mounted. This cabinet serves to house the photographic machine and the light to the lens is adapted to pass through an aperture 15.

The base is shown as provided with a pedestal 16 which has a threaded upper portion 17 thereon. This pedestal receives a threaded post 18. Fixed upon this post is a seat 19 and the construction is such that when the seat 19 is rotated it will be raised or lowered.

The pedestal 16 is provided with an exten-

sion 20 which is hollowed to receive a lever 21 which is pivoted at 22. The end 23 of this lever has a projection thereon which fits a groove 24 on the lower end of the post 18 so that when the post is moved up or down the lever 21 will be rocked.

The lever 21 is connected by means of a link 25 with a bell crank 26 which is pivoted at 27 and which has the arm 28 engaged between two spaced lugs 29 on a sliding member 30. This sliding member at its other end is provided with spaced lugs 31 which receive between them an arm of a bell crank 32. The other arm 33 of the bell crank is connected to a link 34 which is pivoted at 35 to an illuminating lamp 36. This lamp is mounted on a pivot 37 and the construction is such that as the seat 19 is raised the lamp 36 will be swung about its pivot 37 to a very small extent to change the direction of its rays and thereby throw a better light upon the subject being photographed.

The cabinet is provided with a front 40 which is supported upon a projection 41 arranged upon the pedestal 16. The cabinet is also provided with side members 42 which are notched as at 43.

The cabinet is provided with a top 44 which inclines downwardly toward the front as shown in Fig. 2, and which also inclines toward either side so that water falling upon it will be drained away.

The cabinet is preferably composed of a plurality of angle irons 45 upon which the wooden or metallic members comprising the body are mounted. The cabinet may be provided with a mirror 46 for the use of the person being photographed.

The notches 43 are so arranged that the portions 51 of the sides 42 are of sufficient width so that the front edge thereof is about even with the front portion of the subject's face. These portions together with the projecting portion 52 at the top, acting in conjunction with the front 40 and the top serves to exclude direct rays of light from striking the subject's face so that shadows are eliminated. This allows the light from the lamp 36 to properly illuminate the subject without objectionable shadows.

With all photographic machines heretofore constructed and with which I am familiar it has been difficult to secure satisfactory pictures on account of the fact that the lighting arrangement has been poor. On account of police regulations cabinets cannot

be completely enclosed, so that heretofore poor lighting has resulted.

With my improved cabinet the face of the subject is hidden from direct outside light so that the artificial light produced is not interfered with by cross shadows caused by the natural light.

This feature of excluding natural light from the cabinet and at the same time providing artificial light in conjunction with automatic photographic machines, is new as far as I am aware, and I consider this of great importance.

Having thus described my invention, what I claim is:

- 15 1. A photographic cabinet comprising a base, a top, a back, a front, an artificial light, a seat for the subject being photographed, and light excluding strips on each side of the front and extending towards the back.
- 20 2. A photographic cabinet comprising a base having a back thereon, a top, a seat support on said base, a front fixed on said seat support, a side at each edge of the front, a seat on said base, said front terminating adjacent to said seat, said front having side strips thereon.
- 25 3. A photographic cabinet comprising a base, a back, a case for a photographic machine, an artificial light, a seat for the subject being photographed, said case having a front and a top thereon, said case having a strip along each side near the front thereof and also having a strip on either side near the back thereof.
- 30 4. In a photographic cabinet, a base, a case for a photographic machine, an artificial light, a seat for the subject being photographed, and light excluding means on three sides of the place occupied by the subject, said means serving to prevent direct light from striking the subject, said artificial light serving to illuminate the subject.
- 35 5. In a device of the class described, a base having a back thereon, a top fixed on

said back, a support on said base, a front fixed on said support, a pair of sides connecting said front and back and engaging said top, a seat on said base, said sides being notched and each side having one edge thereof disposed alongside of said seat whereby direct light from the sides and front of said cabinet will be cut off from the subject, and means to direct artificial light upon the subject.

6. In a photographic cabinet, a base having a lamp support thereon, a seat on said base, said seat including a threaded pedestal, a threaded post secured on said pedestal, a seat on said post, a lamp pivotally mounted on said support, a pivoted lever adapted to be rocked by said post, a rod pivotally connected to said lamp, and means connecting said lever and said rod for swinging said lamp about its pivot when the seat is raised or lowered.

7. In a photographic cabinet a base having a lamp support thereon, a vertically adjustable seat on said base, a lamp pivotally mounted in said support, and means connecting said lamp and said seat whereby when the seat is raised or lowered the lamp will be swung on its pivot.

8. In a photographic cabinet, a base having a back thereon, a case-supported on said back, a seat on said base, said seat including a threaded pedestal, a threaded post on said pedestal, a seat on said post, a lamp pivotally mounted in said cabinet, a pivoted lever adapted to be rocked by said post, a bell crank, a link connecting said bell crank and said lever, a slid able link adapted to be reciprocated by said bell crank, a second bell crank adapted to be rocked by said slid able link, and a rod pivotally connected to said second mentioned bell crank and to said lamp for swinging said lamp about its pivot when the seat is raised or lowered.

In testimony whereof, I hereunto affix my signature.

ROBERT E. OLSEN.
